UNITED STATES PATENT OFFICE.

JOHN A. HARE, OF NEW YORK, N. Y.

CONTINUOUS-RAIL RAILWAY-CROSSING.

1,305,211.

Specification of Letters Patent. Patented May 27, 1919.

Application filed October 1, 1917. Serial No. 194,175.

To all whom it may concern:

Be it known that I, JOHN A. HARE, residing at New York, in the county of New York and State of New York, have invented certain new and useful Improvements in Continuous-Rail Railway-Crossings, of which the following is a specification.

This invention relates to a continuous-rail railway crossing.

10 The object of the invention is to provide a simple, practical and efficient means whereby to provide a continuous and even surface to be traversed by the car wheels at railway crossings.

15 A further object is to provide means adapted to be controlled by an approaching car in either direction for automatically providing an unobstructed and smooth traction surface for the wheels of that car.

20 A more detailed object is to provide suitable turn tables at the rail intersections, which turn tables are formed to provide portions of the traction surface and are adapted to be automatically turned by an approaching car so as to bring the traction surface of the turn table into proper register for permitting passage of the approaching car.

25 A further detailed object is to provide simple, inexpensive and practical means for simultaneously operating the turn tables at the four or more rail intersections.

30 A further object is to provide means whereby the operating mechanism may be quickly and easily assembled or disassembled.

35 A further object is to arrange the operating mechanism so that it may, if desired, be operated in oil or grease, and whereby it may not be detrimentally affected by changes in temperature or by the presence of snow and ice upon the roadway.

40 A further object is to provide suitable and efficient mountings for the turn tables.

45 A further object is to provide means to insure a full, complete and positive operation of the turn tables at each operation of the automatic control.

A further object is to provide means whereby the degree of rotation automati-

cally imparted to the turn tables by a passing vehicle may be adjusted so as thus to enable the use of similar parts regardless of the angular relation of the crossing rails.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown merely a preferred form of embodiment of the invention.

Figure 1 is a plan view of a railway crossing constructed in accordance with this invention, parts of the structure being broken away so as to better disclose the operating elements for one of the turn tables.

Fig. 2 is a side elevational view of the structure shown in Fig. 1, parts being illustrated in section upon the plane of line II of Fig. 1.

Fig. 3 is an enlarged detail sectional view of one of the automatic control devices, the section being taken substantially upon the plane of line III of Fig. 1.

Fig. 4 is a similarly enlarged sectional view illustrating the parts of Fig. 3 but being taken substantially upon the plane of line IV of Fig. 1.

Fig. 5 is a similarly enlarged sectional view illustrating the construction and arrangement of the parts of one of the turn tables and its mounting and operating elements, the section being taken substantially upon the plane of line V of Fig. 1, and

Fig. 6 is a plan view illustrating a modification in which the invention is shown as applied to railways employing central slots midway between the track rails.

Referring to the drawings for describing in detail the structure which is illustrated therein, the reference character L indicates the turn tables. These are arranged at the intersection of the rails G and each is pro-

designed so as to facilitate easy and correct assembling. To assemble the parts it is simply necessary to slide one of the shafts 7 longitudinally into one of the tubular openings 28, through an entrance hole which is later closed by a screw plug 29. As the shaft is advanced it is threaded through the gears 8 and 9 which are held in the recesses 30. The shaft is moved inwardly so that its squared end passes beyond the adjacent pocket 18. The housing 17, with the pinion and the plunger 10 assembled therein, is then lowered into the pocket and the shaft is pushed backwardly through the squared hole of the pinion.

This process is repeated for each shaft.

After the shafts are in position the turn tables are then lowered into their pockets so that the gears 6 of the turn tables engage the gears 8 of the shafts. The assembly is then complete.

As shown particularly in Fig. 5, each turn table is preferably carried in a separately formed cylindrical carrier, or bearing member, 31. These bearing members are threaded into threaded pockets formed in the body member G so that they become in effect a part of the body member though they may be moved as occasion requires.

The interior of each bearing member is formed to directly receive the turn tables. The inner cylindrical walls of the bearing member are preferably machined so as to form a snug fit with the exterior walls of the turn table, and a packing ring 32 is provided for preventing flow of moisture or the like into the joint between the turn table and the walls of the bearing member. The bottom wall of the bearing member forms a broad and substantial surface upon which the lower end of the turn table is supported. A suitable opening is formed in the bottom wall of the bearing member for the passage of a short shaft 33 which carries the gear 6 at its lower end beyond the bottom wall of the bearing member. The gear 6 is fixed rigidly to the shaft 33.

The engagement of the lower end of the turn table flat against the bottom wall of the bearing member, and the engagement of the lower surface of the bearing member in turn flat against the bottom wall of the threaded pocket of the body member insures a solid metallic support for the turn table so that the upper traction surface of the turn table may not be forced downwardly by the weight of a passing car.

Preferably each turn table is provided with an oil well 34 therein having ducts 35 leading to various parts of the joint between the turn table and the wall of the bearing member. The well 34 is closed by a plug 36 and a small plunger head 37 is arranged in the well. This plunger head is carried upon

a screw 38 which projects through the plug 65 36. Rotation of the screw, as by means of a screw driver or a like tool engaging the upper end of the screw, will cause the plunger head to move downwardly and force the oil through the ducts 35. 70

In the modification Fig. 6, a track crossing is illustrated which employs a central slot 39 such as is used in certain electric railways. In this modification auxiliary, or intermediate turn tables 40 are provided at the points 75 where the slots 39 cross the slots 1 and 2 of the track rails.

These turn tables 40 may be the same as those already described except that the transverse slot is enlarged to meet the requirements of the situation and they are connected to the under-lying shafts 7 for simultaneous operation in the same manner as described for the turn tables L. When they are in one position they provide a continuous 80 85 traction surface for the wheels of the passing vehicle and they provide an open slot for the plow of the vehicle as shown. When in the opposite position they provide continuous traction surface of the slot for a 90 vehicle passing in that direction.

As many changes could be made in this construction without departing from the scope of the invention as defined in the following claims. It is intended that all matter contained in the above description or shown in the accompanying drawings, shall be interpreted as illustrative only and not in a limiting sense.

In order to provide for an adjustment of 100 the degree of rotation automatically imparted to the turn tables by a passing vehicle the plungers 10 are preferably made up of two parts as clearly seen in Fig. 4. These two parts, as 41 and 42, are provided 105 with mating knurled surfaces 43 and they are bolted together by bolts 44 which extend through a slot 45 formed preferably in the part 42. The upper end of the part 42 provides the shoulder 25 which engages the 110 shoulder 24 while the lower end of the part 41 provides the shoulder which engages the bottom wall 26 of the housing.

It is apparent that by adjusting the part 42 upwardly with respect to the part 41 then 115 the shoulder 25 will sooner engage the shoulder 24 and limit the upward movement of the part 41. The possible subsequent downward movement of the plunger, and consequently the possible degree of rotation 120 to be imparted to the shaft 7, is thus determined.

In order to facilitate the introduction of the plunger in its allotted space within the housings 17 said housing is preferably 125 divided as shown at 46. When the screws 44 are screwed home and the plunger is in position, the engagement of the outer ends of the

tersection localities, turn tables at said rail-intersection localities being received in pockets formed in the body part, the body part having an opening extending there-
5 through communicating with said pockets adapted to contain a lubricant for said turn tables, and packings arranged within the pockets in engagement with the turn tables for preventing displacement of the lubri-

cant and for preventing access of foreign 10 matter to the lubricant.

In testimony whereof I affix my signature in the presence of two witnesses.

JOHN A. HARE.
